UNITED STATES PATENT OFFICE

LOUIS W. THOMPSON, OF SCHENECTADY, NEW YORK, ASSIGNOR TO GENERAL ELECTRIC COMPANY, A CORPORATION OF NEW YORK

SOUND AMPLIFIER AND REPRODUCING APPARATUS

Application filed May 10, 1928. Serial No. 276,742.

The present invention relates to apparatus for amplifying and reproducing sounds by electrical means and more particularly to an apparatus of this character which is energized in part at least from a source of alternating current.

Such an apparatus may, for example, be represented by the audio frequency amplifier and sound reproducer of a broadcast or other receiver employing electron-discharge devices of the high vacuum type, the filament or cathode circuits of which are supplied with low voltage alternating current from a source of the usual commercial low frequency.

In a sound amplifying and reproducing apparatus of this character, the pulsations of the low frequency source may be transmitted through the amplifying portion of the apparatus and energize the reproducing device or loud speaker or modulate the current flow therein sufficiently to produce an audible hum. This hum is often faint, and noticeable only when the apparatus is energized but not operating to amplify and reproduce the signals or sounds normally carried by it. The hum is, however, annoying in itself and undesirable, particularly when of such magnitude as to be audibly superimposed upon or mingled with the normal signals delivered by the reproducer or speaker.

In accordance with my invention the undesirable hum effect of low frequency alternating currents in a sound amplifying and reproducing apparatus is avoided by the provision of an improved apparatus and method of operation whereby a neutralizing current of suitable phase and frequency is superimposed on the operating current of the reproducing apparatus.

My invention will be better understood from the following description when considered in connection with the accompanying drawings and its scope will be pointed out in the appended claims.

In the drawings, Fig. 1 is a wiring diagram of a sound amplifying and reproducing apparatus which includes electron-discharge devices having their cathode circuits sup-

plied with alternating current, and means arranged in accordance with the invention for eliminating alternating current hum in the reproducer; and Fig. 2 illustrates a modification in certain details of the apparatus.

Referring to Fig. 1, 5 and 6 are electron-discharge devices connected in any suitable manner for sound amplification, as for example by audio frequency transformers 7, 8 and 9, between a signal or sound input circuit 10 and the armature circuit 11 of a reproducer or loud speaker 12.

The plate or anode supply is taken from any suitable source, such as batteries 13, and the grid and plate return to the cathodes or filaments is carried through midtap resistors or stabilizers 14 across the filament circuit 15 to reach the electrical center of the filament connection with alternating current supply. Filament current is taken from a suitable source of alternating current, such as a house lighting circuit 16 of the usual voltage and low frequency through a step down transformer 17.

The loud speaker 12 may be of any suitable type and in the present example is represented as being of the dynamic cone type having an armature coil 18 connected with the output circuit 11 of the amplifier. Coil 18 represents the actuating coil or winding of any sound reproducing device. The field of the loud speaker of the present example is provided by a magnet indicated at 19 and a coil 20 energized from a constant voltage source, such as a battery 21.

The amplifier and reproducer arrangement above described is shown only by way of example as illustrating an apparatus to which the method and means of the present invention is applicable. It consists essentially, for purposes of illustrating and describing the invention, of an amplifier for an electrical sound reproducer, certain of the circuits of which amplifier are supplied with alternating current.

In the operation of the apparatus a small amount of alternating current gets into the operating winding of the loud speaker along with the signal or operating current. In order to neutralize the hum produced by this

stray current in the operating winding of the loud speaker a neutralizing current taken from the low frequency supply circuit 16 through a suitable step down transformer 22 is fed into the loud speaker or amplifier output circuit 11 at such a phase angle and magnitude with respect to the hum or stray current as to exactly neutralize the effect of the latter.

- 10 The means employed in the present example for doing this comprise a circuit 23 connected to the output or speaker circuit 11 and including a resistor or potentiometer 24—25, and a neutralizing current supply circuit 26 connecting taps 27 on the resistor with the secondary of a transformer 22, through a variable inductance 28.
- 15

Inductance 28 represents any suitable reactance means in the neutralizing current supply circuit which may be varied to vary the phase angle of the neutralizing current whereby it will oppose the hum current. For example it may comprise an inductance 29 and capacitance 30 connected in shunt as shown in Fig. 2. As shown, the capacitance is variable, although either or both may be made variable to provide the necessary reactance to bring the neutralizing current into proper phase relation with the hum or stray current in the loud speaker to neutralize the effect of the latter current.

20 The magnitude of the neutralizing current is varied by means of the taps 27 on resistor 24. In the present example one tap is made variable with respect to the other to increase and decrease the magnitude of the neutralizing current, an increase being effected as it is moved away from the other along the resistor.

- 25 40 While but one neutralizing circuit 26 is generally sufficient to eliminate the hum, it is obvious that others may be connected in a similar manner, each tapped into resistor 24, with a variable reactance in circuit, as shown for circuit 26, to neutralize a plurality of hum or stray currents or harmonics thereof.

From the foregoing description it will be seen that the neutralizing current is taken preferably from the same source as the hum or stray current, so that having a common source, variations in the voltage or frequency of the source do not appreciably affect the neutralized condition in the loud speaker once it has been attained. This method of eliminating hum and undesirable noises in the reproducer is readily carried out by simple means which are easily applied to any amplifier and reproducer, as by the resistor in the reproducer or output circuit and a reactance controlled supply circuit connecting the resistor with the sources of hum.

30 While the invention is not limited to these means, the use of a reactance and resistance means in a circuit connecting the source of stray current with the operating winding or

35 circuit of the reproducer as shown is at present considered to be the preferred form of the invention because of its simplicity, and effective control of the phase angle and magnitude of the neutralizing current. The use of the 40 source of the hum or stray current as the source of the neutralizing current automatically compensates for variations in the magnitude and frequency of the hum or stray current since the neutralizing current will 45 vary correspondingly and tend to maintain the neutralization substantially constant. However, any other suitable source of neutralizing current may be used.

50 What I claim as new and desire to secure by Letters Patent of the United States, is:

55 1. The method of neutralizing the hum effect of stray alternating current in a sound reproducer operated in connection with an alternating current energized amplifier, said stray current being present in the signal current supplied to said reproducer from said amplifier, which comprises supplying alternating current to the armature winding of the reproducer from the same alternating current source as the amplifier at a controlled 60 value and phase angle with respect to said stray alternating current.

65 2. The method of neutralizing the hum effect of stray alternating current in a sound reproducer, said stray current being present in the signal current supplied to said reproducer, which comprises supplying alternating current of a frequency corresponding to that of the stray current to the armature winding 70 of the reproducer at a controlled value and phase angle with respect to said stray alternating current.

75 3. The method of neutralizing the hum effect of stray alternating current in a sound reproducer, said stray current being present in the signal current supplied to said reproducer, which comprises supplying alternating current from the source of the stray alternating current to the armature winding of the 80 reproducer at a controlled value and phase angle with respect to said stray alternating current.

85 4. The method of neutralizing the hum effect of stray alternating current in a sound reproducer, said stray current being present in the signal current supplied to said reproducer, which comprises supplying alternating current to the armature winding of the 90 reproducer along with the signal and stray current at a controlled value and phase angle with respect to said stray current and from the same source as said stray current.

95 5. The combination with an electrical apparatus comprising an amplifier connected to alternating current supply terminals and a reproducer connected with the amplifier, of means for supplying alternating current from said terminals directly to said reproducer, means for varying the phase angle of 100

said current, and means for varying the magnitude of said current.

6. In combination, an electrical sound amplifying apparatus having an output circuit, an alternating current supply circuit connected with said amplifying apparatus, a reproducer connected with said output circuit, and means for supplying a neutralizing alternating current to said output circuit independently of the amplifying apparatus.

7. In combination, an electrical sound amplifying apparatus, having an output circuit, an alternating current supply circuit connected to the cathode heating circuit of said amplifying apparatus, and means for supplying a neutralizing alternating current to said output circuit from said alternating current supply circuit independently of the amplifying apparatus.

20 8. In combination, an electrical sound amplifying apparatus, having an output circuit, an alternating current supply circuit connected with said amplifying apparatus, a reproducer connected with said output circuit, means for supplying a neutralizing alternating current to the output circuit and reproducer independently of the amplifying apparatus, said means comprising a resistor connected in said output circuit, an alternating current supply circuit connected with the resistor, and a variable reactance in said last-named circuit.

9. In combination, an electrical sound amplifying apparatus having an output circuit, an alternating current supply circuit connected with said amplifying apparatus, a reproducer connected with said output circuit, means for supplying a neutralizing alternating current to the output circuit and reproducer from the alternating current supply circuit independently of the amplifying apparatus, said means comprising a resistor connected in said output circuit, said resistor having spaced taps, at least one of which is movable along the resistor, a neutralizing current circuit connecting the alternating current supply circuit with the resistor at said spaced taps, and a variable reactance in said neutralizing current circuit.

50 10. The combination with an electrical amplifying and reproducing apparatus embodying electron discharge devices and means providing a source of alternating current for energizing certain of the operating circuits of said devices, of means for supplying alternating current from said source directly to the reproducing portion of said apparatus, and means in circuit with the reproducing portion of said apparatus for varying the phase angle and magnitude of said alternating current.

11. In combination, an amplifier embodying electron discharge devices and having an output circuit, an alternating current supply circuit with which the filaments of said

devices are connected, a reproducing device connected with the amplifier output circuit for receiving the amplified output therefrom, and means providing a connection between the alternating current supply circuit and the amplifier output circuit whereby said output circuit receives current directly from said supply circuit, said means being variable to vary the phase angle and magnitude of said current.

In witness whereof, I have hereunto set my hand this 9th day of May, 1928.

LOUIS W. THOMPSON.
